UNITED STATES PATENT OFFICE.

ALEXANDER D. CURRY, OF HAWKINSVILLE, GEORGIA.

TIE-PROTECTOR.

1,191,496.

Specification of Letters Patent. Patented July 18, 1916.

Application filed November 29, 1915. Serial No. 64,077.

To all whom it may concern:

Be it known that I, ALEXANDER D. CURRY, a citizen of the United States, residing at Hawkinsville, in the county of Pulaski and

5 State of Georgia, have invented certain new and useful Improvements in Tie-Protectors, of which the following is a specification.

This invention relates to the class of railway ties and fasteners, and more specifically 10 to tie protectors.

The object of my invention is to provide a sheet metal protector primarily designed for use upon the end portions of wooden railway ties. It is a matter of common knowledge 15 that the life of a wooden railway tie is rather short, even when treated specially to withstand the elements. It is also a well-known fact that rotting and disintegration of the ties in the great majority of cases 20 starts at the ends of the ties. This is caused by the pounding of the loads carried by the ties causing the grain of the wood near the ends to separate, thereby permitting water to seep into the wood, which causes it to rot.

25 The object of my invention is two-fold; the protector tends to bind the wood together at the ends of the tie, thus preventing it from feathering along the grain as much as it otherwise would were my protector not 30 used, and furthermore, it sheds water from the top of the tie at the ends thereof, and by means of outwardly extending flanges directs the water away from the side and end of the tie and also prevents the sun's rays 35 from reaching the wood; moisture and sun being the chief destroying elements of wooden ties.

Other objects of this invention not at this time more particularly enumerated, will be 40 clearly understood from the detailed description and drawings forming a part of this specification.

Furthermore, this invention consists in the novel arrangement and combination of parts 45 more particularly described in the following specification and embodied in the claim appended hereunto and forming a part of this application.

Referring now to the drawings, which are 50 merely illustrative of my invention, Figure

1 is a perspective view of my tie protector applied. Fig. 2 is a perspective view of my tie protector showing the interior face thereof.

Referring further to the drawings, where- 55 in similar reference characters designate similar parts throughout the respective views, 1 designates the top face of my tie protector, adapted to seat upon the top of a tie near the end thereof, and formed with a 60 rectangular end piece 2, the inner face of which is adapted to abut the end of a tie, and side plates 3 formed integral with said top face 1 and adapted to seat adjacent the sides of a tie. The end plate 2 and side 65 plates 3 are formed with an outwardly extending flange 4 integral with the lower edge thereof. A plurality of perforations 5 are provided through the top face 1 adapted to receive spikes 6 to secure the protector upon 70 the end of a tie 7.

The utility, adaptability, and advantages 75 of my improved form of tie protector being obvious, it is unnecessary to further enlarge upon the same herein.

Having now described and pointed out the new and useful features of my invention, I do not limit myself to the shape of certain parts where the shape is not essential, nor do I restrict myself to the exact details of construction shown and described, but mean and intend to claim all equivalents and variations thereof, not departing in principle from my invention, and falling within the purview of the appended claim. 85

What I claim as my invention and desire 80 to secure by Letters Patent is:

A tie protector consisting of a rectangular cap member adapted to fit upon the top of the end portion of a railway tie, said cap 90 being provided with perforations therethrough, securing elements adapted to be inserted through said perforations for fastening said cap upon said tie, and an outwardly disposed flange formed integrally with the 95 rim of said cap member.

In testimony whereof I affix my signature hereto.

ALEXANDER D. CURRY.
